UNITED STATES PATENT OFFICE.

JACOB C. LOWREY, OF WILMINGTON, DELAWARE, ASSIGNOR OF ONE-HALF
TO HENRY M. LOVE, OF WILMINGTON, DELAWARE.

DESIGN FOR RIBBED KNITTED FABRIC.

SPECIFICATION forming part of Design No. 35,439, dated December 10, 1901.

Application filed October 14, 1901. Serial No. 78,661. Term of patent 14 years.

To all whom it may concern:

Be it known that I, JACOB C. LOWREY, a citizen of the United States, and a resident of Wilmington, Delaware, have invented and produced a new and original Design for a Ribbed Knitted Fabric, of which the following is a specification.

My design is fully shown in the accompanying drawings, in which—

10 Figure 1 is a diagrammatic view of a piece of fabric, illustrating the pattern thereof; and Fig. 2 is a detailed view, on a much larger scale, of a piece of fabric, illustrating the different character of the stitches whereby the design is produced.

15 The design consists of a knitted ribbed fabric, having the appearance substantially as shown in the accompanying drawings, wherein there are parallel stripes *a* and *b*, the stripes *a* being throughout of an open-work character, due to the employment in the formation of the same of what are known as "tuck-stitches," and the stripes *b* being composed of

alternate blocks *c* and *d*, the blocks *c* being of open-work character, owing to the employment of tuck-stitches in their fabrication, while the blocks *d* are of closer texture because of the employment of plain knitting in the fabrication of these blocks. The stitches composing the wales *f* are drawn to one face 25 of the fabric and the stitches composing the wales *g* are drawn to the opposite face of the fabric. 30

Having thus described my invention, I claim and desire to secure by Letters Patent—

The design for a ribbed knitted fabric substantially as described and as shown in the accompanying drawings.

In testimony whereof I have signed my name to this specification in the presence of two subscribing witnesses.

JACOB C. LOWREY.
